UNITED STATES PATENT OFFICE.

GOTTLÖB BINDER, OF ROCHESTER, NEW YORK, ASSIGNEE TO AMERICAN LAUNDRY MACHINERY COMPANY, OF CINCINNATI, OHIO, A CORPORATION OF OHIO.

IRONING-MACHINE.

1,195,553.

Specification of Letters Patent. Patented Aug. 22, 1916.

Application filed July 27, 1914. Serial No. 853,266.

To all whom it may concern:

Be it known that I, GOTTLÖB BINDER, of Rochester, in the county of Monroe and State of New York, have invented certain new and useful Improvements in Ironing-Machines; and I do hereby declare the following to be a full, clear, and exact description of the same, reference being had to the accompanying drawings, forming a part of this specification, and to the reference-numerals marked thereon.

My invention relates to ironing machines, and more particularly to presses of the class which embodies a heated bed or platen and work support, one of said parts having movement relatively to the other to bring them into pressing relation with each other, and it has for its object to improve the construction of this class of machines with a view particularly to adapting an apparatus to the more efficient finishing of what are known in the trade as work shirts.

More specifically, the invention resides in the application of certain improvements to an ironing machine for use in shirt factories, for the production of work shirts, where it is desirable to finish a shirt at a single operation as quickly and economically as possible, after it has already been made and folded. A work shirt is finished by subjecting the folded shirt to a pressing operation, and a further purpose of my invention is to afford means for readily stretching the shirt and smoothing the surface thereof immediately prior to the final pressing.

To these and other ends the invention consists in certain improvements and combinations of parts all as will be hereinafter more fully described, the novel features being pointed out in the claims at the end of the specification.

In the drawings: Figure 1 is a side view of a machine constructed in accordance with a preferred embodiment of my invention; Fig. 2 is an end elevation; Fig. 3 is an end elevation looking in the opposite direction from Fig. 2; Fig. 4 is an enlarged side elevation of the work support; Fig. 5 is a plan view of the work support, showing the flexible plate lowered, with a shirt appearing in dotted lines, and Fig. 6 is a side elevation of the work support, partially in section.

Similar reference numerals throughout the several figures indicate the same parts.

In order to afford a proper preliminary understanding of the nature and use of my invention, it may be stated that it is the general practice in the manufacture of low priced work shirts to press the shirt after it has been made and folded, the folds being pressed into the article so that it presents a fairly neat appearance when ready to be sold, but in view of the low cost of this class of shirts, it is necessary that the time and expense involved in pressing the goods be reduced to a minimum. The machine that I have devised is especially useful in this relation although there are other possibilities for the application of the structure wherever it may be desirable to employ a flexible plate to be brought down upon work on a work support preliminarily to a final pressing operation, one of the chief functions of the flexible plate being to stretch the upper surface of the shirt and straighten out the folds or creases that have resulted during the previous handling.

In the present embodiment illustrating a convenient method for carrying out my invention, A is the frame or body of the machine provided at one end with a pair of standards B and C and at its opposite end with a single standard C' upon which is mounted the turret D. The latter is rotatable on the standard C' and provided with a pair of work supports, one of which is adapted to be moved to pressing position while the other one is being prepared by the removal of a finished shirt and the positioning of a fresh one, all as is well known in this type of ironing machinery. The standards are connected by a head E, on which is arranged the stationary heated bed or plate F with which the work support operates, and to which a heating medium is supplied in any desirable manner.

Each work support consists of a board or carrier for the shirt to be pressed, as designated at G, the said board being mounted on a casting *a* which is provided with a central post *b*. The turret D includes a collar *c* which receives a sleeve or socket *d* that is movable vertically with relation thereto and carries at its upper end a flange or shoulder *e* for engagement with the upper end

of the collar *c*. The work support is yieldably mounted on the turret, and to this end the aforementioned post *b* engages the sleeve or socket *d* and is resiliently supported 5 therein.

g designates a spring arranged at the bottom of the sleeve *d* and engaged by a follower *h* which is mounted on a spindle *i*, the latter being adjustably threaded in the 10 casting *a* as shown in Fig. 6. The casting *a* is also provided with posts *j* which engage suitable guiding openings in the turret and are surrounded by springs *k* that are arranged between the casting *a* and the turret 15 so as to cushion the downward movement of the work support when it is lowered, as will be described presently.

The work support is elevated into engagement with the heated bed by a means 20 that will later be set forth and I will now describe the means for retaining the shirt in position and for smoothing and straightening the surface thereof prior to the pressing operation. To accomplish this, 25 I employ a flexible plate, preferably of metal, that is normally elevated above the work support. The plate may be of arched formation so that as it is brought downwardly into flattened engagement with the 30 shirt, it will progressively engage the upper surface of the latter and in this manner serve to stretch it more or less and remove the folds or wrinkles that have resulted from previous handling. The board 35 *g* is provided with a pair of arms or brackets *l* in which is mounted the spindle *m*. *H* designates the flexible plate that is provided with arms *n* which are journaled upon the spindle *m*. The plate *H* is normally 40 elevated above the work support, so as to permit of readily positioning a shirt, and for this purpose I employ a rest *o* which is mounted on a stationary bracket *p* and curved to conform substantially to the normal 45 curvature of the plate *H*. In order to retain the flexible plate against the rest *o*, the latter may be provided with retaining means for this purpose, and in the present embodiment I have illustrated a convenient 50 device that co-operates successfully with a metal plate and consists of a permanent magnet *q*. Upon positioning a shirt on the work support the plate *H* is drawn away from the retaining device and let down upon 55 the shirt, first assuming the position shown in Fig. 6, after which the free end of the plate is pulled toward the work support causing the plate to progressively and gradually come into contact with the upper 60 surface of the shirt until it is in flattened engagement, as shown in Figs. 4 and 5. The plate is provided with a handle *r* and also with a latch *s* adapted to engage a projection *t* on the board and to thereby 65 hold the plate in flattened engagement as

shown in Figs. 4 and 5. When the latch *s* is released by means of the finger-piece *u*, the plate springs upwardly to the position shown in Fig. 6, and can be readily thrown to its vertical position in engagement with the retaining magnet *q*. In Fig. 5, there appears in dotted lines an outline of the usual formation of a folded work shirt, and in order to prevent the collar points from being pressed into the body portion of the shirt, I may employ supplemental plates such as shown at *x* to be arranged between the body portion at the front of the shirt and the collar points, thereby preventing the formation of unsightly ridges or creases. 80

In Fig. 1, one of the work supports is shown in pressing position while the remaining one is out of pressing position. The turret is held in proper position by means of a spring actuated locking bolt *a'* 85 which co-operates with corresponding recesses *b'* on the turret. The locking bolt *a'* carries a head *c'* at its lower end and co-operating therewith is an arm *d'* fixed upon a shaft *e'* which is automatically rocked to 90 lower the locking bolt and release the turret as the work support is lowered away from the heated bed. The work support is elevated by means of a projection *f* carried by a pivoted lever *g'*, which is operated by suitable treadle controlled mechanism, and engages the sleeve or socket *d*, elevating the latter, and with it the work support when the treadle *h'* is depressed. *i'* designates a releasing treadle which carries a slotted arm 100 *j'* co-operating with a pin *k'* on an arm *l'* fixed upon the shaft *e'*. When the treadle *i'* is lowered, it causes the treadle *h'* to be released, permitting the work support to be lowered away from the heated bed and at 105 the same time releasing the turret so that it can be rotated to reverse the positions of the work supports.

It is to be understood that my invention is not to be limited to the precise arrangement herein disclosed, for I intend to cover by this application any modifications or adaptations of the novel features that are contemplated by the appended claims.

I claim as my invention:

1. In an ironing machine, the combination with a heated bed, of a work support, a flexible plate pivotally mounted at one end of the support substantially coextensive with the latter and adapted to entirely cover the work on the support, and means for holding the opposite end of the plate in engagement with the work support. 115

2. In an ironing machine, the combination with a heated bed, of a work support, a flexible plate pivotally mounted on the support substantially coextensive with the latter and adapted to entirely cover the work on the support, the free end of the plate being normally raised above the support, and 120

means for holding said free end of the plate in engagement with the support.

3. In an ironing machine, the combination with a heated bed, of a work support, a flexible plate pivotally mounted on the support substantially coextensive with the latter and adapted to entirely cover the work on the support, said plate being normally arched away from the support, and means for holding the plate in flattened engagement with the support.

4. In an ironing machine, the combination with a heated bed, of a work support, a flexible plate having one end mounted on the support substantially coextensive with the latter and adapted to entirely cover the work on the support, the plate being normally arched upwardly with its free end in spaced relation above the support, and means for holding the plate in flattened engagement on the work support.

5. In an ironing machine, the combination with a heated bed, of a work support, a

flexible plate pivotally mounted at one end to the work support substantially coextensive with the latter and adapted to entirely cover the work on the support, and means carried by the plate at its opposite end and having engagement with the work support.

6. In an ironing machine, the combination with a heated bed, of a work support, a flexible plate pivotally mounted at one end to the work support, and means coöperating with the plate to hold it elevated on the work support.

7. In an ironing machine, the combination with a heated bed, of a work support, a flexible metal plate pivotally mounted at one end on the work support, and a magnet coöperating with the plate to hold it elevated on the support.

GOTTLLOB BINDER.
